GAS DETECTOR

André Blanchard, Houston, Tex., assignor to
 Schlumberger Well Surveying Corporation,
 Houston, Tex., a corporation of Delaware

Application July 11, 1946, Serial No. 682,961

2 Claims. (Cl. 73—19)

1
 The present invention relates to apparatus for detecting the presence of gas in a liquid. More specifically, it relates to a new and improved apparatus for detecting the presence of gas in the drilling mud which is customarily used to facilitate drilling operations in the oil industry.

It is the usual practice in drilling oil wells by the rotary method to circulate a water or oil base drilling mud in the bore hole, which serves both as a coolant and for bringing the drill cuttings to the surface. When the drill penetrates into a gas bearing sand during the course of drilling operations, a quantity of the gas enters the drilling mud stream and is carried to the surface with the drill cuttings. The presence of this gas in the drilling mud is a detriment to proper operation since it tends to lighten the weight of the mud column and thus increase the danger of a blowout. For this reason, it is highly desirable for the driller to know when the drill has reached a gas bearing formation, in order that he may take steps to increase the density of the drilling mud until the hydrostatic pressure of the mud column at any depth is greater than the natural formation pressure at that depth.

Heretofore, some difficulty has been encountered in determining when the drill has reached a gas bearing formation. This difficulty arises in part from the fact that the penetration of a gas bearing formation does not result in any considerable continuous flow of gas into the drilling mud stream. On the contrary, the amount of gas entering the mud stream is generally only slightly more than is present in the part of the formation removed by the drill. This gas is carried to the surface where it expands and is released into the atmosphere. Since it is relatively small in quantity and is given off only during a relatively short period of time, it is difficult to detect. It is entirely possible, therefore, for the drill to traverse a gas zone without the knowledge of the driller.

It is an object of the invention, accordingly, to provide a new and improved apparatus for detecting the presence of gas in a liquid such as the drilling mud in an oil well, for example.

A further object of the invention is to provide a method and apparatus of the above character in which the properties of compressional waves are utilized for providing indications of the presence of gas in the drilling mud.

Another object of the invention is to provide a novel gas detecting apparatus of the above character which is adapted to operate automatically and unattended to provide a continuous

record of gas content versus time or drill depth, and/or to actuate a warning signal when the gas content in the drilling mud exceeds a safe amount.

5 In accordance with the invention, the presence of gas in the drilling mud of an oil well is detected by transmitting compressional wave energy through the drilling mud stream at the surface and observing the attenuation of such wave energy produced by varying amounts of gas contained in the drilling mud. More specifically, the invention comprises the steps of producing wave energy, preferably but not necessarily in the acoustic range, at a submerged point in the mud stream, and obtaining at another submerged point in the mud stream indications of the wave energy transmitted through the liquid between the two points.

10 It has been determined that the efficiency of propagation of compressional waves through a liquid is greatly influenced by the presence of gas in the liquid. It has been found that the presence of even a small amount of gas in the liquid results in a marked reduction in the ability **15** of the liquid to transmit wave energy. Other conditions being fixed, the amount of absorption or attenuation of the acoustic wave energy is related to the volume of the gas carried in the liquid. In general, the greater the percentage **20** volume of the gas, the poorer will be the transmission of acoustic waves by the liquid.

25 Since the acoustic wave transmission properties of the liquid depend on the percentage volume of the gas contained therein, it will be apparent that gas detectors relying on absorption or attenuation of wave energy for their operation are not suitable for lowering in deep bore holes. In deep oil wells, the ambient pressure is invariably very high so that the greater portion of **30** any gas present is in its liquid phase, and only a small portion is in the gaseous phase. For this reason, it is proposed, according to the present invention, to detect the presence of gas in the drilling mud at the surface or very near the point of exit of the mud stream, where the major portion of the gas in the mud stream is in the gaseous phase.

35 Additional objects and advantages of the invention will be apparent from the following detailed description of a preferred embodiment, taken in conjunction with the accompanying drawings, in which

40 Figure 1 is a schematic view in vertical section of a drill in a bore hole, showing the man-

ner in which the drilling mud is circulated through the bore hole, and

Figure 2 is a view in perspective of apparatus constructed according to the invention for detecting the presence of gas in the drilling mud.

In Figure 1, a conventional type drilling apparatus 10 is shown in a bore hole 11. Drilling mud is pumped by suitable pumping apparatus (not shown) through the drill pipe 12 to the drilling head 13 where it flows into the bore hole 10 through the openings 14. The drill cuttings from the bottom of the bore hole 10 are carried by the mud to the top of the bore hole where they flow through a trough or conduit 15 into a sump 16 from which the mud is recirculated through the bore hole 10. Gas detecting apparatus D constructed according to the invention is submerged in the mud in the trough 15 at the surface of the earth, so that the mud stream flows through it.

Referring now to the Figure 2, the gas detecting apparatus D comprises an open-ended cylindrical conduit 17 submerged in the mud stream flowing through the trough 15. A source of acoustical energy 18 such as a vibrating diaphragm, for example, is positioned in one side of the conduit 17. The acoustical energy source 18 may be energized by any suitable source such as a fixed frequency oscillator 19, for example. The oscillator 19 may include any suitable number of power amplifier stages as required to produce a high enough energy level for proper operation. A receiver 20, which may be another microphone, is placed a short distance, from three inches to two feet, for example, from the transmitter 18. The receiver 20 may be positioned within the conduit 17 or in an opposite wall thereof, as shown. Preferably the receiver 20 is positioned so that it will face the transmitter 18, in which case it will receive maximum energy therefrom.

Indications of the intensity of the acoustical energy received by receiver 20 may be obtained in any conventional manner. One of many possible indicating systems may comprise, for example, an amplifier 21 which receives the output of the receiver 20, the output of which may be indicated by a suitable alternating current meter. If desired, the output of the amplifier 21 may be changed to a variable direct current by a conventional detector or rectifier 22, the magnitude of the signal being indicated on a direct current meter 23. In a field unit, the meter 23 will usually be of the recording type. Any conventional alarm or warning means may be connected in the output circuit such as in series or in parallel with the meter 23, and adjusted so that the alarm will sound when the output is less than a predetermined value.

The conduit 17 should preferably be constructed of a material which absorbs sound waves readily. Also, both the material and the shape of the conduit 17 should be such as to insure that a minimum of wave reflection exists.

It will be apparent that the construction of the units 18 and 20 should be such as to permit their operation while submerged in the drilling mud. If microphones or headphone units are employed, they may be encased in a thin rubber jacket. Preferably, the acoustical generator should be of the type disclosed in the co-pending patent applications of Andre Blanchar, Serial Nos. 578,529, now Patent No. 75

2,451,797 and 578,531, now abandoned, filed February 17, 1946.

In operation, the conduit 17 and associated transmitter 18 and receiver 20 are submerged in the mud stream in the trough 15 (Figure 1) such that at least a representative part of the flow passes continuously through the conduit 17 and the conduit 17 is maintained full of fluid. The ends of the conduit 17 may be flared and the tube oriented so that a stream line mud flow through the conduit 17 results. As the rate of flow is generally low, this can be accomplished quite readily.

The transmitter 18 is then energized at a constant frequency and power level by the oscillator 19, thereby creating acoustical wave energy that is propagated through the drilling mud to the receiver 20. The more gas there is present in the mud, the less will be the energy that is received at the receiver 20. The output of the receiver 20, which is a function of the acoustical energy impinging upon it, is amplified, if necessary, by the amplifier 21. The output of the amplifier 21 may be changed to direct current by the rectifier 22 and may be recorded by recording meter 23. The concentration of gas present in the drilling mud may be readily determined by comparing the reading of the meter 23 with a previously prepared calibration chart which gives meter readings versus different known mixtures of drilling mud and gas. If the danger point gas concentration has been determined, the alarm or warning device may be adjusted to operate at the meter reading corresponding to this critical value.

It will be apparent from the foregoing that the invention provides a highly satisfactory apparatus for detecting the presence of oil in drilling muds. By determining the absorption or attenuation of compressional wave energy propagated through the mud stream near the surface of the earth, in accordance with the invention, the presence of relatively small quantities of gas in the drilling mud can be readily detected.

Other suitable devices for creating the acoustic wave energy of constant intensity, and other means for indicating the intensity of the acoustical energy received, will be readily apparent to those skilled in the art, the specific apparatus shown being only schematic and typical. Therefore, the novel apparatus disclosed herein should be considered as illustrative of the invention and not as limiting the scope of the appended claims.

I claim:

1. Apparatus for detecting the presence of gas in the circulating drilling mud stream in an oil well comprising an open-ended conduit submerged in said mud stream at the surface of the earth and disposed so as to facilitate the flow of said mud stream therethrough, a compressional wave energy transmitter mounted at one side of said conduit, a constant intensity source of wave energy for said transmitter, a compressional wave energy receiver mounted at another side of said conduit in the path of wave energy transmitted from said transmitter through the mud stream, and means responsive to the output of said wave energy receiver.

2. Apparatus for detecting the presence of gas in the circulating drilling mud stream in an oil well comprising an open-ended conduit submerged in said mud stream at the surface of the earth and disposed so as to facilitate the flow of said mud stream therethrough, a compressional wave energy transmitter mounted at

one side of said conduit, a constant intensity source of wave energy for said transmitter, a compressional wave energy receiver mounted at another side of said conduit in the path of wave energy transmitted from said transmitter through the mud stream, means for amplifying and rectifying the output of said wave energy receiver, and means connected to said amplifying and rectifying means and providing a warning signal when the output of said wave energy receiver reaches a predetermined value.
